UNITED STATES PATENT OFFICE.

ERASTUS E. WINKLEY, OF LYNN, MASSACHUSETTS.

AUTOMATIC SHOE MACHINE.

1,082,185.

Specification of Letters Patent. Patented Dec. 23, 1913.

Application filed July 23, 1909. Serial No. 509,961.

To whom it may concern:

Be it known that I, ERASTUS E. WINKLEY, a citizen of the United States, residing at Lynn, in the county of Essex and State of Massachusetts, have invented certain new and useful Improvements in Automatic Shoe-Machines; and I do hereby declare the following to be a full, clear, and exact description of the invention, such as will enable others skilled in the art to which it appertains to make and use the same.

The present invention relates to machines for operating upon boots and shoes in which the shoe and operating means are relatively movable to transfer the point of operation of the operating means around the shoe, and in which the relative movements between the shoe and means for operating thereon are automatically affected and controlled, so that the shoe is properly presented to the operating means as the point of operation is transferred around the shoe.

The object of the invention is to provide an automatic machine of this character having an improved construction which renders its operation more uniform, certain and reliable.

To this end the invention contemplates the provision in a machine in which the means for operating on a shoe and a shoe supporting jack are relatively movable to transfer the point of operation of the operating means around the shoe, of novel and improved means for determining the point about which the relative swinging movements which are imparted to the jack and operating means shall take place, whereby the swinging movements may be made to take place about the point of operation of the operating means without strain upon the parts of said means which are in engagement with the shoe; the provision of improved means for imparting the relative feeding movements to the jack and operating means to transfer the point of operation of the operating means around the shoe, whereby the proper feeding movements are affected without undue strain upon those parts of the operating means which operate by engagement with the shoe to impart relative feeding movements to the shoe and operating means; and the provision of improved means for controlling the operation of mechanism which acts to automatically correct the relative position of the operating means and shoe as the point of opera-

tion of the operating means is transferred around the shoe, whereby the correcting mechanism is operated at proper intervals during the transfer of the point of operation around the shoe, and is properly timed with relation to the operation of the operating means.

The various features of the invention will be readily understood from an inspection of the accompanying drawings, in which—

Figure 1 is a side elevation of a machine embodying the various features of the invention; Fig. 2 is a vertical longitudinal section of the machine shown in Fig. 1; Fig. 3 is a detail elevation of parts of the mechanism for controlling the correcting mechanism; Fig. 4 is a plan view, partially in section, of the devices shown in Fig. 3; Fig. 5 is a vertical sectional view on line 5—5, Fig. 3; Fig. 6 is a detail plan view partly in section of a part of the devices for timing the operation of the correcting mechanism; Fig. 7 is an end elevation, partly in section, of the parts shown in Fig. 6; Fig. 8 is a detail elevation, partly in section, showing parts of the feeding mechanism and the devices for determining the point about which the jack swings; Fig. 9 is a similar view to Fig. 8, looking at the devices from the other side; Fig. 10 is a front elevation of the devices shown in Fig. 9, looking toward the left in Fig. 8; Fig. 11 is a plan view of the devices shown in Figs. 8 to 10; Fig. 12 is a horizontal sectional view on line 12—12, Fig. 8; Fig. 13 is a sectional detail view of the feeding gripper; Fig. 14 is a sectional detail on line 14—14, Fig. 12; Fig. 15 is a detail showing certain parts of the tripping mechanism; Fig. 16 is a transverse vertical sectional view showing parts to be described; Fig. 17 is a rear view of the driving shaft with the frame shown in section; Fig. 18 is a sectional detail on line 18—18, Fig. 17; and Fig. 19 is a sectional view on line 19—19, Fig. 17.

In the construction shown the features of the invention are embodied in a machine in which the means for operating upon the shoe consists of a sewing mechanism which is substantially the same in construction as the well-known Goodyear welt and turn shoe sewing machine shown and described in Patent No. 412,704, October 8, 1889. The shoes to be operated upon are carried upon a jack, and correcting mechanism is provided for giving the relative movements to

the sewing mechanism and jack requisite for properly presenting the shoe to the sewing mechanism as the point of operation is transferred around the shoe. The relative movements requisite to transfer the point of operation around the shoe are effected by imparting longitudinal and swinging movements to the jack, and the requisite relative longitudinal and transverse tipping or tilting movements are effected by movement of the support on which the sewing mechanism is carried.

The sewing mechanism is mounted upon a supporting carrier 1 and is provided with the usual channel guide, back gage, feeding awl and stitch forming instrumentalities. The support 1 is mounted to slide on segmental ways 2 formed on a head 3 which is mounted to turn in suitable bearings 4 and

5 formed in the frame of the machine. The segmental ways are formed concentric with the point of operation of the sewing mechanism, so that the lateral tilting movements imparted to the sewing mechanism by sliding the support 1 on the ways 2 take place about the point of operation of the sewing mechanism. The bearings for the head 3 are so arranged that the axis about which the head turns passes through the point of operation of the sewing mechanism, so that the longitudinal tilting movements imparted to the sewing mechanism by rocking the head 3 also take place about the point of operation of the sewing mechanism.

35 Movements are imparted to the support 1 to vary the lateral inclination of the sewing mechanism by a cam 6 secured to a cam shaft 7 and connected to control the position of the support 1 on the ways 2. The cam 6 is arranged to engage a roll on the end of an arm 8 projecting from a sleeve 9 which is pivotally mounted upon the frame of the machine (Fig. 16). The sleeve 9 is provided with a second arm 10, the end of which is connected by an adjustable link 11 with one end of the bell crank lever 12. The other end of the bell crank lever is provided with two arms 13 arranged to engage a ring 14 which is mounted on a sleeve 15 surrounding the hollow shaft 16 of the head 3.

50 The sleeve 15 is connected with a rod 17 by means of a pin 18 which passes through the sleeve and rod, and through longitudinal slots 19 formed in the hollow shaft 16. The rod 17 is mounted to slide within the hollow shaft, and the forward end of the rod is connected by a link 20 with one end of the bell crank lever 21, the other end of which is connected by a link 22 with the support

55 1. Through these connections the position of the support 1 upon the ways 2 is controlled and varied by the cam 6 to correct the relative lateral inclination of the sewing mechanism and shoe in accordance with the 60 part of the shoe being operated upon.

The position of the head 3 is controlled and varied to determine the longitudinal inclination of the sewing mechanism by a cam 23 connected to impart rocking movements to the head. The cam is arranged to engage a roll 24 on the end of an arm 25 which projects from a sleeve 26 pivotally mounted on the frame of the machine. The sleeve 26 is provided with a projecting arm 27, the outer end of which is connected by a link 28 with a lug 29 formed on the head 3. A spring 27' arranged to engage an arm 28' on the sleeve 26 holds the roll 24 in engagement with the cam (Fig. 16). Through these connections the cam 23 acts to correct the relative longitudinal inclination of the sewing mechanism and shoe in accordance with the part of the shoe being operated upon.

The jack upon which the shoe to be operated upon is supported is provided with a base 30, and with heel and toe supports 31 and 32 for supporting a lasted shoe. The jack is secured upon the upper end of a shaft 33, which is mounted to rotate and slide vertically in bearings formed in the outer end of a supporting arm 34. The rear end of the arm 34 is mounted to turn freely upon a shaft 35 which is mounted in bearings in the outer end of a second arm 36. The rear end of the arm 36 is mounted to turn freely upon a shaft 37 which is mounted in fixed bearings 38 formed in the frame of the machine. This construction permits the jack to be moved freely in any horizontal direction in transferring the point of operation of the sewing mechanism around the shoe, and in presenting the shoe supported upon the jack in proper position to be operated upon by the feeding and stitch forming devices of the sewing mechanism. The jack is forced yieldingly upward to press the shoe against the channel guide during the sewing operation by a spring 39 connected to one end of a bell crank lever 40 the other end of which engages a collar 41 secured to the jack carrying shaft 33.

Longitudinal movements are imparted to the jack by the feeding awl of the sewing mechanism, and by an auxiliary feed which will be described later. Swinging movements are imparted to the jack to correct the relative position of the shoe and sewing mechanism as the point of operation of the sewing mechanism is transferred around the shoe by a cam 42 secured to the shaft 7, and connected to impart rotary movements to the jack carrying shaft 33. The cam is arranged to engage a roll carried by the lower end of a lever 43, the upper end of which is connected to a sliding bar 44. The bar is provided on one side with rack teeth arranged to engage a pinion 45 which is secured to the lower end of the shaft 37. The

shaft 37 is connected with the shaft 35 by intermeshing gearing 46, and the shaft 35 is connected with the shaft 33 by intermeshing gearing 47. Through these connections 5 the cam 42 acts to impart rotary movements to the shaft 33 to swing the jack, and thus correct the relative position of the shoe and sewing mechanism as the point of operation of the sewing mechanism is transferred 10 around the shoe.

The swinging movements are imparted to the work by rotating the jack carrying shaft 33, the devices of the sewing mechanism are in engagement with the shoe at the point of 15 operation of the sewing mechanism, and the swinging movements of the work take place about the point of operation, the jack supporting arms swinging to permit the swinging movement of the work to take 20 place about this point, although the axis of the shaft 33 does not pass through the point of operation. The devices of the sewing mechanism which engage the work will thus act to cause the swinging movement to take 25 place about the point of operation, but since this swinging movement involves a bodily movement of the jack and the jack supporting arms, more or less strain is put upon the devices which engage the work at the 30 point of operation, and under some conditions this strain is liable to cause a displacement of the work which will interfere with the proper operation of the sewing mechanism upon the shoe. In order to relieve the 35 devices of the sewing mechanism from strain, and in order to avoid all danger of a displacement of the work as the jack is swung, means is provided which acts independently of the devices engaging the 40 work to cause the work to swing about the point of operation of the means for operating upon the shoe. In the construction shown these devices consist of a clamp, the jaws 48 and 49 of which are arranged to 45 grip a plate 50 in line with the point of operation of the sewing mechanism upon the shoe. The plate 50 is secured to the jack carrying shaft 33, and has an outline corresponding generally to the shape of a shoe 50 sole, so that the marginal portion of the plate may travel between the jaws of the 55 clamp as the jack is moved longitudinally and swung during the sewing operation. The jaws of the clamp are so arranged that a line passing through the point of operation of the sewing mechanism, and parallel with the axis of the jack carrying shaft 33, will pass through the axis of the clamping 60 jaws. When the clamp is engaged with the plate 50, therefore, it will form a pivot or fulcrum about which the jack will swing when the jack carrying shaft 33 is rotated, and as this pivot is in line with the point of operation of the sewing mechanism upon

the shoe, the clamp will insure the swinging 65 of the jack about the point of operation independently of the engagement of the sewing mechanism with the shoe. The fixed jaw 48 of the pivot clamp consists of a stud mounted for rotation in the outer end of a 70 fixed arm 51, and the movable jaw 49 of the clamp consists of a similar stud mounted for rotation in the outer end of a lever 52 mounted beneath the arm 51. The lever 52 is operated to clamp and release the plate 50 75 by means of a piston 53 arranged in a cylinder 54, and provided with a piston rod 55, the lower end of which engages the rear end of the lever 52. A spring 56 is arranged between the lower end of the cylinder and 80 the piston, and tends to raise the piston and thus unclamp the plate 50. The upper end of the cylinder is connected through a pipe 57 with devices for supplying compressed air. When the compressed air is admitted to the 85 pipe 57, it acts to force down the piston and thus operate the lever 52 to clamp the plate 50 between the jaws 48 and 49.

The feeding awl of the sewing mechanism will operate to advance the work and thus 90 move the jack longitudinally. In order to assist the awl in feeding the shoe, or to relieve it of the strain incident to overcoming the inertia and friction of the jack supporting 95 devices, a supplemental feeding mechanism is provided for imparting movements to the jack in unison with the feeding movements of the awl. In the construction shown this supplemental feeding mechanism comprises a feeding gripper or clamp 100 arranged to act upon the plate 50, and operated to impart feeding movements to the plate and connected jack substantially co-extensive with the feeding movements of the awl. The feeding gripper comprises an arm 58 105 pivotally mounted in the support 59 to swing about a vertical axis (Figs. 8, 9, 10, 11 and 13). The arm 58 is provided at its forward end with a stud 60 mounted to turn freely in the end of the arm, and provided with a head for engaging the upper surface of the plate 50. The movable jaw of the gripper comprises a similar stud 61 pivotally mounted in the end of a lever 62 which is pivoted to the arm 58. The rear end of the lever 62 110 is engaged by the lower end of a piston rod 63, the upper end of which carries a piston 64 arranged within a cylinder 65. A spring 66 is interposed between the piston and the upper end of the cylinder, and tends to operate the lever 62 to grip the plate 50 between the jaws 60 and 61 of the feeding gripper. The lower end of the cylinder is connected through a pipe 67 with a supply of compressed air, and when the air pressure is 115 on it forces the piston up against the tension of the spring 66, thus disengaging the jaws 60 and 61 from the plate 50. The sup-

ply of air through the pipe 67 is controlled by mechanism to be described to operate the gripper to clamp and release the plate 50 at proper intervals, as will be more fully explained hereafter. Feeding movements are imparted to the feeding gripper while the jaws 60 and 61 are in engagement with the plate 50 through a lever 68, the upper end of which is connected by a pivotal joint 69 with an arm 70 which extends at right angles from the arm 58. The lower end of the lever 68 is connected to the outer end of a piston rod 71, the inner end of which is provided with a piston 72 arranged within a cylinder 73. A spring 74 is interposed between the outer end of the cylinder and the piston 72, and tends to move the piston in a direction to advance the feeding grippers. The rear end of the piston is connected through a pipe 75 with devices for supplying compressed air to the piston. When the outer end of the cylinder is in communication with the supply of compressed air, the air pressure acts to advance the piston and return the feeding gripper to its retracted position.

The supply of compressed air to the cylinders 54 and 65 for controlling the opening and closing of the pivot clamp or gripper and the feeding clamp or gripper, and the supply of compressed air to the cylinder 73 for controlling the feeding movements of the feeding gripper, is controlled by a valve 76 which is intermittently operated by a cam 77 secured to the cam shaft 78 of the sewing machine. The pipes 57, 67 and 75 are led to the cylinders 54, 65 and 73 respectively, which connect with a distributing union 79 which is in turn connected through a pipe 80 with the supply port 81 of the casing 82 within which the controlling valve 76 is mounted (Figs. 1, 5 and 7). The valve 76 is connected to a lever 83, the end of which carries a roll engaging the cam 77. The end of the lever is acted upon by a spring pressed pin 84 which holds the roll in engagement with the cam, and tends to hold the valve 76 in such position that there is open communication between the supply port 81 and the ports 85 which are in communication with a compressed air supply through a pipe 86. The cam 77 is so arranged that as the feeding movement of the feeding awl of the sewing mechanism is about to begin, the lever 83 is moved to cut off communication between the supply port 85 and the port 81, and open communication between the port 81 and the exhaust ports 87. The cam 77 holds the valve 76 in this position until the feeding movement of the awl is completed, and then allows the valve to return to its previous position, thus putting the pipe 80 into communication with the supply of compressed air. The pipe 80 is therefore in communication with the supply of compressed air except

during the periods when the feeding of the work is taking place. The compressed air, therefore, acting on the pistons 53, 64 and 72, acts normally to hold the pivot clamp in engagement with the plate 50, to hold the feeding gripper out of engagement with the plate 50, and to hold the feeding gripper in its retracted position. When the cam 77 operates the valve 76 to relieve the air pressure upon the pistons 53, 64 and 72, the springs 56 and 66 act to disengage the pivot clamp from the plate 50 and to engage the feeding gripper with the plate 50, and the spring 74 tends to force the feeding gripper forward to advance the jack in the direction of the feeding movement of the feeding awl. The spring 56 is somewhat stronger than the spring 74, so that the feeding gripper is operated to grip the plate 50 before the spring 74 acts to advance the feeding gripper. The engagement of the feeding gripper with the plate 50 before it is given an advancing movement may also be insured by so constructing the spring 66 that it will act to close the feeding gripper before the spring 53 acts to disengage the pivot clamp. During the feeding movement of the feeding awl, the feeding gripper is forced forward by the spring 74 to assist in the feed of the work, and to overcome the inertia and friction of the jack supporting devices. The proper feed of the work is thus insured without putting unusual strain upon the feeding devices which engage the work.

The feeding movements imparted to the jack and shoe during the sewing operation to transfer the point of operation of the sewing mechanism about the shoe, causes the jack and shoe to move in a horizontal plane. So long, therefore, as the sewing mechanism is held in mid-position longitudinally, that is, in such position that the awl moves in a horizontal plane during its feeding movement, the movement imparted to the work and jack will be the same as the feeding stroke of the awl. Whenever the sewing mechanism is tilted longitudinally, however, the awl will move in an inclined plane, while the jack and shoe will still move in a horizontal plane. The movement imparted to the shoe and jack, therefore, will in such case be less than the stroke of the awl, and the decrease in the movement imparted to the shoe and jack by the awl will depend upon the extent to which the sewing mechanism is tilted longitudinally. The feeding gripper always operates in a horizontal plane, and the feeding impulse imparted to the jack and shoe by the feeding gripper will always be the same as the stroke of the gripper. In order that the feeding impulse imparted to the work by the feeding gripper may accurately coincide with the feeding movement imparted

to the work by the awl, means is provided for varying the feeding stroke of the gripper in accordance with the variation produced in the feed by the longitudinal tilting movement of the sewing mechanism.

In the construction shown, the mechanism for varying the throw of the feeding gripper when the sewing mechanism is tilted longitudinally comprises a sliding bar 88 arranged to be engaged by a roll 89 on the outer end of the piston rod 71, and thus determine the initial position of the feeding gripper preparatory to its feeding advance stroke. This bar is provided with controlling surfaces 90 extending above and below the point on the bar which is normally engaged by the roll 89 when the feeding gripper is in its retracted position. The lower end of the bar 88 is connected by a pin and slot connection with the outer end of an arm 91 which is secured to one end of a rock shaft 92. The other end of the rock shaft is provided with an arm 93 which is connected by a link 94 with one of the arms 25 27 which projects from the sleeve 26 through which longitudinal tilting movements are imparted to the sewing mechanism. Whenever the sewing mechanism is given a longitudinal tilting movement, the bar 88 is moved either up or down from its normal position, thus moving one or the other of the inclined controlling surfaces 90 into position to engage the roll 89. This movement of the bar 88 thus advances the 35 feeding gripper so that its feeding stroke is shortened. The extent to which the feeding stroke of the gripper is shortened will depend upon the extent to which the bar 88 is moved, and therefore the feeding 40 stroke of the gripper will be varied in accordance with the longitudinal tilting of the sewing mechanism. The controlling surfaces 90 are so formed that the feeding stroke of the feeding gripper is varied in 45 accordance with the variation in the feeding of the shoe by the feeding awl, caused by the longitudinal tilting of the sewing mechanism. The swinging of the jack between two succeeding feeding strokes of the 50 feeding awl will also cause a decrease in the movement imparted to the shoe and jack by the awl. Means is accordingly provided for varying the feeding stroke of the feeding gripper in accordance with the 55 variation in the movement imparted to the shoe and jack caused by the swinging of the jack between successive feeding movements. In the construction shown this means comprises a second slide bar 95 similar to the 60 bar 88, and arranged to be engaged by a second roll 96 mounted on the front end of the piston rod 71. This bar is provided with two inclined controlling surfaces 97 extending above and below the point which 65 is normally engaged by the roll 96, as in-

dicated in Fig. 8. The lower end of the bar 95 is connected by a pin and slot connection with an arm 98 projecting from a clutch member 99. The clutch member 99 is mounted upon a fixed horizontal stud 100, and carries a helical clutch sleeve 101 which surrounds the hub 102 of a beveled gear 103 which is mounted to turn on the stud. The clutch sleeve 101 is operated by a lever 104 pivoted on the clutch member 99, 70 and provided with a wedge block 105 for operating the clutch sleeve. The outer end of the operating lever 104 engages the conical end 106 of a hollow piston rod 107 which is connected with a piston 108 arranged in 75 a cylinder 109 (Fig. 12). A spring 110 is arranged between the inner end of the cylinder and the piston, and tends to withdraw the piston rod and thus release the clutch sleeve 101 from clutching engagement with the hub of the gear 103. The rear end of the cylinder 109 is connected through a pipe 111 with the distributing union 79 heretofore described. When the air pressure is admitted to the cylinder, it forces the piston forward against the tension of the spring 110, and operates the clutch sleeve 101 to 80 lift the hub of the beveled gear 103. The clutch member 99 is normally held in position to maintain the bar 95 with the neutral point between the inclined surfaces 97 in 85 position to be engaged by the roll 96. The means for thus holding the clutch member in normal position, and for returning the clutch member to this position when the clutch sleeve 101 is disengaged from the hub of the gear 103, comprises a spring 112 coiled about the hub of the gear 103, and having its ends arranged to lie upon opposite sides of two pins 113 and 114. The pin 113 is a fixed pin which projects from an arm formed on the stud 100 while the pin 114 projects from the clutch member 99. The spring tends to hold these two pins in 90 line, as indicated in Figs. 12 and 14. The gear 103 is engaged by a beveled gear 115 which is connected with a spur gear 116 arranged to mesh with that one of the gears 95 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900

inclined controlling surface advances the feeding gripper so that its next feeding stroke is shortened, and the decrease in the length of the feeding stroke will depend upon the extent to which the bar 95 is moved. The extent to which the bar 95 is moved will in turn depend upon the swinging movement which is imparted to the jack, and therefore the feeding stroke of the feeding gripper will be varied in accordance with the swinging movement imparted to the jack preceding such feeding stroke. As the feed is about to begin, the valve 76 is operated in the manner already described, and relieves the air pressure in the cylinder 109 so that the piston 108 is operated by the spring 110 to release the clutch member 99 from the gear 103, so that the spring 112 may return the clutch member to normal position. Thus the feeding stroke of the gripper next succeeding a swinging movement of the jack is automatically varied in accordance with the swinging movement imparted to the jack, and the controlling surfaces 97 are so formed that the variation corresponds to the variation in the movement imparted to the shoe and jack by the feeding awl caused by the swinging of the jack.

30 The shaft 7 which carries the cams of the correcting mechanism is given a partial revolution to vary the relative position of the sewing mechanism and shoe as certain points are reached during the transfer of the point of operation of the sewing mechanism around the shoe. The mechanism for thus intermittently operating the correcting mechanism comprises a clutch which is thrown into operation at the proper time during the transfer of the point of operation about the shoe, and which when thrown into operation makes a single revolution and then is automatically thrown out. The points in the transfer of the point of operation about the shoe at which the correcting mechanism is thrown into operation is determined by a controller which is connected to move with the jack. In the form shown, this controller comprises a plate 117 which is secured to the jack carrying shaft 33. The plate has the general outline of a shoe sole, and is provided with a series of downwardly projecting pins 118 which act as trips to determine the points in the relative travel of the shoe and operating means at which the correcting mechanism is thrown into operation. In order that the relative movements imparted to the jack and sewing mechanism by the correcting mechanism may be properly and uniformly timed with relation to the operation of the sewing mechanism upon the shoe, mechanism is also provided for properly timing the operation of the correcting mechanism in relation to the operation of the sewing mechanism.

Through the combined action of these two controlling mechanisms the correcting mechanism is operated at the proper intervals during the transfer of the point of operation of the sewing mechanism about the shoe in proper time, and its operation is uniformly and properly timed to effect the changes in the relative position of the sewing mechanism and shoe when the devices of the sewing mechanism are in a predetermined relation.

70 The mechanism for intermittently operating the shaft 7 which carries the cams of the correcting mechanism comprises a clutch 119, one member of which is constantly driven through a main friction driving clutch 120, and the other member of which is secured to a shaft 121. The shaft 121 is connected through change gearing 122 with a shaft 123 which carries a worm 124 engaging a worm wheel 125 secured to the shaft 7. The intermittently operating clutch 119 may be of any suitable construction, and as shown is a form of "Horton" clutch. The ball carrying ring or sleeve for effecting the engagement and disengagement of the clutch is indicated at 126, and the throwing of the clutch into and out of operation is controlled by the arm 127 of a stop lever 128 which is normally held in position to engage a shoulder on the ball carrying ring by a spring 129 (Fig. 17). The stop arm 127 of the stop lever is provided with a cushioning spring 130 which is engaged by the shoulder on the ball carrying ring 126 and serves to cushion the blow when the clutch is thrown out of operation. A brake 121' for stopping the shaft 121 when the clutch is thrown out of operation is also provided, and this brake mechanism is operated by a brake lever 131. When the brake and stop levers are operated, the clutch 119 is thrown into operation, and after the shaft 121 has made a single revolution, the clutch is thrown out and the brake mechanism thrown in, the clutch lever having been released and returned to normal position during the rotation of the shaft, and the brake lever being released as the shaft completes its revolution. During the revolution of the shaft the brake mechanism is held out of action by a cam 132 arranged to engage a roll on the brake lever.

105 The mechanism for operating the brake and clutch levers to throw the correcting mechanism into operation comprises a lever 133, the lower end of which is arranged to engage the upper ends of the brake and clutch levers, and the upper end of which is pivotally connected to a sliding rod 134. The rod is acted upon by a spring 135, which tends to force the rod in a direction to operate the clutch and brake levers to throw the driving mechanism into operation. The rod 134 is held in normal position against 110

130

the tension of the spring 135 by a latching toggle 136 arranged to hold the lever 133 in retracted position when the links of the toggle are straightened, as indicated in Fig. 5 2. One link of the toggle carries a roll arranged to be engaged by a resetting cam 137 during the rotation of the shaft 121. The toggle 136 is broken to throw the driving mechanism into operation by means of a 10 rod 138, the lower end of which is arranged to strike the toggle. This rod is forced in a direction to break the toggle by a spring 139. The rod 138 is normally held in retracted position against the tension of the 15 spring 139 by a latch bar 140 provided with a pin 141 which is arranged to engage one arm 142 of a bell crank lever, the other arm 143 of which is connected to the upper end of the rod 138 (Figs. 3, 4 and 5). The pin 20 141 on the latching bar 140 is held in projected position by a spring 144 for a purpose which will be hereinafter described. The latching bar 140 is forced in a direction to disengage the pin 141 from the arm 142, 25 and thus release the toggle actuating rod 136 by a spring 145. The bar is normally held in latching position against the tension of the spring 145 by a pivoted latching dog 146 arranged to engage a shoulder 147 30 on the bar. The latching dog is held yieldingly in position to engage the shoulder on the latching bar by a spring pressed pin 148. The means for operating the latching dog 146 to release the latching bar, and thus 35 throw the driving mechanism for the correcting mechanism into operation, comprises a vertically sliding pin 149 arranged above the latching dog 146 and engaged by the lower end of a piston rod 150, the upper end of which is provided with a piston 151 mounted within a cylinder 152. The upper end of the cylinder is connected by a pipe 153 with the port 154 of a valve casing 155 (Fig. 7). A valve 156 is mounted within 40 the valve casing 155, and controls the supply and exhaust of compressed air through the pipe 153. The valve 156 is acted upon by a spring 157 which tends to force the valve in a direction to open communication between the pipe 153 and the supply ports 158 which are connected through a pipe 159 with a compressed air supply. The operation of the valve 156 is controlled by a cam 160 secured to the cam shaft 78 of the 45 sewing machine. This cam is provided with a depression 161, and when this depression is in register with the end of the valve 156 the valve is operated to supply compressed air to the pipe 153. This supply of compressed air forces the piston 151 downward, and operates the pin 149 to disengage the 50 dog 146 at a definite period in the cycle of operations performed by the sewing mechanism, provided movement of the pin 149 is 55 not prevented when the recess in the cam 160 registers with the valve 156. By this mechanism the proper timing of the operation of the correcting mechanism with relation to the operation of the sewing mechanism is insured. The disengagement of the dog 146 from the latching bar by the supply of compressed air to the piston 151 at each revolution of the cam shaft of the sewing mechanism is normally prevented by a controlling slide 162 arranged to normally lie between the pin 149 and the latching dog 146, and having its outer end supported upon a fixed support 163. This controlling slide 60 normally prevents the disengagement of the dog 146 from the latching slide. The inner end of the slide 162 is pivotally supported upon the vertical arm of a bell crank lever 164, and when this slide is withdrawn so that its outer end is not supported upon the support 163, the pin 149 is free to operate 65 upon the latching dog 146 when the compressed air is admitted to the cylinder 152. The slide 162 is thus withdrawn to determine the points in the travel of the point of operation of the sewing mechanism about 70 the shoe at which the correcting mechanism shall be thrown into operation by devices actuated by the trip pins 118 on the controller plate 117 which is connected to move with the jack. The connections through 75 which the tripping pins actuate the controller plate 117 comprise a bar 165, the rear end of which is pivotally supported upon a pivoted arm 166, and the front end of which is arranged to engage the edge of the controller plate 117, the end of the bar being held in engagement with the controller plate by a spring 167 acting upon the arm 166. A slide 168 is mounted in the front end of the bar 165, and carries a latch lever 169, 80 the front end of which is arranged in the path of the trip pins 118. The latch lever is mounted upon a pivot 170, and is held in normal position against the stop 171 by a spring pressed pin 172. The latch lever is 85 connected to operate a detent 173 which is also pivoted on the pivot 170, and the rear end of which is arranged to engage a lug 174 on the bar 165. The detent is forced yieldingly into normal position by a 90 spring 175. The rear end of the slide 168 is connected by a link 176 with one arm of a bell crank lever 177 which is mounted upon the bar 165, and the other end of which is connected by a link 178 with one arm 179 of a three-arm lever 180. A second arm 181 of the three-arm lever is connected by a link 182 with one arm of a bell crank lever 183, the other arm of which is arranged to engage and operate the bell crank lever 164 to 95 which the controller plate 117 is pivoted. The third arm 184 of the three-arm lever 180 is acted upon by a spring 185 which tends to swing the lever 180 in a direction to 100

8
 retract the slide 168 at the front end of the bar 165, and also to withdraw the controller plate 162 from engagement with its support 163. The parts are held in normal position against the tension of the spring 185 by the engagement of the detent 173 on the plate 168 with the lug 174 on the bar 165. When one of the trip pins strikes the latch lever 169 during the feed of the jack and shoe, the detent 173 is disengaged from the lug 174, so that the spring 185 operates to withdraw the controlling plate 162 from engagement with its support 163, and also to retract the slide 168. When this occurs the pin 149 is operated at the proper time during the cycle of operations performed by the sewing mechanism to throw the driving mechanism for the correcting mechanism into operation. The rearward movement of the slide 168 brings a finger 186 on the front end of the slide into the path of the trip pins, so that the passage of a second trip pin past the latch lever 169 is prevented until the parts are returned to normal position. Whenever the controlling devices are operated to throw the driving mechanism for the correcting mechanism into operation, they should be reset before the next succeeding feed of the shoe takes place. The resetting mechanism in the form shown comprises a cam 187 carried by the shaft 121 and arranged to engage a roll carried upon the lower end of a rod 188. The upper end of the rod 188 is connected to an arm 189 which is secured to a rock shaft 190. The rock shaft carries a second arm 191, the upper end of which is arranged to engage an adjustable collar 192 secured to the end of the latching bar 140. The rock shaft 190 also carries a third arm 193, the upper end of which is connected with one end of a rod 194. The other end of the rod 194 passes through a hole in the arm 184 of the lever 180, and is provided beyond the arm with adjustable nuts 195 for engaging the arm. During the rotation of the shaft 121 after the driving clutch therefor has been thrown into operation, the resetting cam 187 operates the rod 188 to rock the shaft 190. During this rocking movement of the shaft 190 the arm 191, acting against the collar 192, retracts the latching bar 140 against the tension of the spring 145, so that the latching dog 146 may reengage the shoulder 147. This movement of the rock shaft 190 takes place before the clutch controlling toggle 136 is turned or reset, and the end of the lever 142 is therefore in front of the end of the pin 141. For this reason the pin 141 is spring supported, so that it may yield as the latching bar 140 is reset. After the latching bar is reset, and when the toggle 136 is straightened, the arm 142 moves down below the pin 141 so that the pin snaps forward over the

end of the arm, thus latching the toggle operating rod 138 in retracted position. The rocking movement of the rock shaft 190 also operates the rod 194 to swing the lever 180 against the tension of the spring 185, so that the bell crank lever 183 and the slide 168 at the front end of the bar 165 are returned to normal position. As the slide 168 is thus returned to normal position, the detent 173 snaps in position in front of the lug 174, so that the parts are latched in position against the tension of the spring 185. Before the shaft 121 completes its revolution, the cam 187 releases the rod 188, so that the rock shaft 190 returns to normal position. 80

In sewing around the toe of a shoe it is desirable that a swinging movement be imparted to the jack after each feeding movement, and means is accordingly provided for withdrawing the controller plate 162 from engagement with its support 163 during the transfer of the point of operation of the sewing mechanism about the toe, so that the correcting mechanism is thrown into operation during each cycle of operations performed by the sewing mechanism. In the construction shown, the means for thus withdrawing the controller plate 162 comprises a cam 196 secured to the shaft 7, and arranged to operate upon a roll carried by the upper end of an arm 197 which is secured to a rock shaft 198. The rock shaft 198 carries a second arm 199, which is connected by means of a link 200 with the bell crank lever 184 to which the controller plate 162 is pivoted. The upper end of the link 200 is connected with the bell crank lever by means of a slot 201 engaging a pin on the bell crank lever, so that the operation of the bell crank lever by the devices which are operated by 90 the trip pins 117 is not interfered with (Figs. 2, 4 and 16).

In order that the same controller plate 117, and the same arrangement of pins 118 may be utilized in sewing different sizes of 110 shoes of the same style, means is provided for moving the front end of the bar 165 in the direction of the feed of the jack, and for varying the extent of this movement in accordance with the size of the shoe to be 115 sewed. For this purpose the front end of the bar 165 is supported in a guide block 202 which is pivotally mounted on the end of a lever 203. The rear end of the lever 203 is connected by a link 204 (Fig. 10) with the upper end of an arm 205 secured to a rock shaft 206. The rock shaft carries a second arm 207 which is connected by a link 208 with an arm 209 projecting from a sleeve 210 which is loosely mounted on the 125 shaft 7. The sleeve 210 is provided with a second arm 211, the upper end of which is pivotally connected to one end of a link 212. The other end of the link 212 is pivotally connected to a slide mounted in a slot 130

formed in an arm 213 which projects from a rock sleeve 214. The sleeve 214 is provided with a second arm 215, the lower end of which carries a roll arranged to engage a cam 216 secured to the shaft 7. The link 212 is connected by a rod 217 with a vertically adjustable slide 218. The slide is provided with a rack which is engaged by a pinion 219, to which an adjusting hand wheel 219' is connected. By these connections the tripping devices carried by the front end of the bar 165 may be moved by the cam 216 in the direction of travel of the trip pins, so that the effect is the same as if the distance between the pins was varied while the arrangement of the pins remains the same. By adjusting the end of the link 212 in the arm 213, the extent to which the latching devices are moved may be varied 20 in accordance with the size of the shoe to be sewed, no movement being imparted to the latching devices when the pivotal connection between the link and arm 213 is in line with the axis of the sleeve 214. Indicating devices may be employed in connection with the adjusting mechanism to indicate the proper adjustment for different sizes of shoes.

The machine is provided with devices 30 operated by a treadle 220 through which the operator may throw the main friction clutch 120 into operation to start the machine, and is provided with devices operated by a cam 221 for automatically disengaging the clutch after the sewing of the shoe has been completed. The devices for throwing the main clutch 120 into and out of operation are best shown in Figs. 16 and 19. As here shown, the main clutch 120 is provided with a movable member 222 which is secured to a sleeve 223 and is forced in a direction to engage the members of the clutch by a spring 224. The driving pulley 225 is secured upon the sleeve 223. 40 The sleeve is forced in a direction to disengage the driving member 222 of the clutch through a bell crank lever 226, one arm of which is provided with adjustable screws 227 for operating upon the sleeve 223, and the other end of which is connected with one link of a toggle 228. The links of the toggle are forced in a direction to disengage the clutch member 222 by a spring 229, and are forced in a direction to allow the engagement of the clutch by a pneumatic piston 230. The piston is mounted in a sleeve 231, the rear end of which is connected by a pipe 232 with a valve casing 233. A valve 234 is mounted in the valve casing 233 and 50 controls communication between the pipe 232 and a supply pipe 235 which is connected to a source of compressed air. The valve 234 is connected to the treadle 220, and also to the lower end of a lever 236.

The upper end of the lever 236 is connected 65 to the lower end of an arm 237 which extends downward from a sleeve 238 mounted on a stud 239. The arm carries a roll 240 which is engaged by the cam 221. The roll is held in engagement with the cam by a spring 241. When the lever 220 is operated by the operator, the valve 234 is shifted to open communication between the supply pipe 235 and the pipe 232, and thus admit air back of the piston 230, so that the clutch 75 operating mechanism is operated to engage the main clutch. After the cam shaft 7 has made a complete revolution, the valve 234 is shifted by the cam 221 to shut off communication between the supply pipe 235 80 and the pipe 232, so that the pressure back of the piston 230 is relieved, and the spring 229 operates to disengage the clutch. The cam shaft 7 is stopped in position when the main clutch is disengaged by a stop lever 242, the lower end of which carries a roll engaging a cam on the cam shaft, and the upper end of which is connected to a spring pressed bar 243 by a link 244 (Fig. 16).

The operation of the valve 234 in starting the machine may also admit compressed air to a pipe 245 which leads to devices (not shown) for throwing the thread tension into operation, the tension on the thread being relieved when the air is shut off from the pipe 245 in stopping the machine after the sewing of the shoe has been completed.

When the main clutch 120 is engaged, the sewing mechanism is continuously driven through a belt 246 which passes over a pulley 247 secured to the driven member of the clutch. The belt also passes over a double pulley 248 mounted upon a stud the axis of which is in line with the axis of the head 3. A belt 249 passes around the double pulley 248 over suitable guide-pulleys and about the driving pulley 250 of the sewing machine. Through these connections the sewing mechanism is continuously driven without interfering with the movements of the machine in correcting the relative position of the sewing mechanism and shoe.

While the various features of the invention have been shown and described applied 115 to a sewing machine for attaching the upper or welt and upper to the insole of turn or welt shoes, it will be understood that the features of the invention are not confined in their application to such a machine, but 120 may be embodied in various machines for operating upon boots and shoes, such as outsole stitchers, lasting machines, pegging machines, and so forth. It will also be understood that the specific construction and arrangement of the parts is not material except so far as the same may be specified in the claims, and that the construction and

arrangement of the various parts may be modified and changed without departing from the broad scope of the invention.

Having explained the nature and object 5 of the invention, and specifically described one machine in which it may be embodied, what I claim is:—

1. An automatic shoe machine, having, in combination, means for operating on a shoe, 10 a shoe supporting jack movable to transfer the point of operation of said means around the shoe and supported for lateral swinging movement to maintain the portion of the edge of the last or shoe sole in proximity 15 to the operating means in substantially the same position with relation to the direction of feed, and devices independent of the operating means and acting independently of the movements of the jack in transferring 20 the point of operation around the shoe for constraining the jack to swing laterally about the point of operation of the operating means as such point is transferred around the shoe, substantially as described.
- 25 2. An automatic shoe machine, having, in combination, means for operating on a shoe and a shoe supporting jack relatively movable to transfer the point of operation of the operating means around the shoe, mechanism 30 acting automatically as the point of operation is transferred around the shoe to impart relative turning movements to the jack and operating means to maintain the portion of the edge of the last or shoe sole 35 in proximity to the operating means in substantially the same position with relation to the direction of feed, and devices other than the operating means and turning mechanism for causing the relative turning movements to take place about the point of operation 40 of the operating means as such point is transferred around the shoe, substantially as described.
3. An automatic shoe machine, having, in 45 combination, means for operating on a shoe, a shoe supporting jack longitudinally movable and rotatable to transfer the point of operation of the operating means around the shoe, mechanism acting automatically as the 50 point of operation is transferred around the shoe to impart turning movements to the jack, and devices other than the operating means and turning mechanism for causing the jack to swing about the point of operation 55 of the operating means as such point is transferred around the shoe, substantially as described.
4. An automatic shoe machine, having, in 60 combination, means for operating on a shoe including devices for feeding the shoe by engagement therewith, a shoe supporting jack longitudinally movable and rotatable to transfer the point of operation of the operating means around the shoe, mechanism 65 acting automatically to impart turning

movements to the jack as the point of operation of the operating means is transferred around the shoe to correct the relative position of the shoe and operating means, and devices other than the operating means and turning mechanism for causing the jack to swing about the point of operation of the operating means as such point is transferred around the shoe, substantially as described.

5. An automatic shoe machine, having, in combination, means for operating on a shoe, a shoe supporting jack, a support freely movable in its plane of movement upon which the jack is rotatably mounted, mechanism acting to automatically impart turning movements to the jack as the point of operation of the operating means is transferred around the shoe to correct the relative position of the shoe and operating means, and devices other than the operating means and turning mechanism for causing the jack to swing about the point of operation of the operating means, substantially as described.

6. An automatic shoe machine, having, in combination, means for operating upon a shoe, a shoe supporting jack movable and rotatable to transfer the point of operation of said means around the shoe, mechanism acting to automatically impart turning movements to the jack, pivot devices the axis of which passes through the point of operation of the operating means, and means for connecting said pivot devices with the jack to cause the jack to swing about the point of operation of the operating means as such point is transferred around the shoe, substantially as described.

7. An automatic shoe machine, having, in combination, means for operating on a shoe, a shoe supporting jack movable and rotatable to transfer the point of operation around the shoe, mechanism acting to automatically impart turning movements to the jack, a plate connected to move with the jack, and devices intermittently engaging the plate to determine the point about which the jack swings as the point of operation of the operating means is transferred around the shoe, substantially as described.

8. An automatic shoe machine, having, in combination, means for operating on a shoe, a shoe supporting jack movable and rotatable to transfer the point of operation of the operating means around the shoe, mechanism acting to automatically impart turning movements to the jack, a plate connected to move with the jack, and devices for gripping the plate as the point of operation is transferred around the shoe to determine the point about which the jack swings, substantially as described.

9. An automatic shoe machine, having, in combination, means for operating on a shoe,

5 a shoe supporting jack movable and rotatable to transfer the point of operation of the operating means around the shoe, mechanism acting to automatically impart turning movements to the jack, a plate connected to move with the jack, and a pivot clamp 10 acting to intermittently grip the plate as the point of operation of the operating means is transferred around the shoe, substantially as described.

10: An automatic shoe machine, having, in combination, means for operating on a shoe, a shoe supporting jack, a support freely movable in its plane of movement upon 15 which the jack is rotatably mounted, mechanism acting automatically to impart turning movements to the jack as the point of operation is transferred around the shoe, a plate connected to move with the jack, 20 and devices intermittently engaging the plate to determine the point about which the jack swings as the point of operation of the operating means is transferred around the shoe, substantially as described.

25: 11. An automatic shoe machine, having, in combination, means for operating on a shoe, a shoe supporting jack, a support freely movable in its plane of movement upon which the jack is rotatably mounted, mechanism 30 acting automatically to impart turning movements to the jack as the point of operation of the operating means is transferred around the shoe, a plate connected to move with the jack, and a pivot clamp 35 acting to intermittently grip the plate to determine the axis about which the jack swings, substantially as described.

12. An automatic shoe machine, having, in combination, means for operating on a 40 shoe and a shoe supporting jack relatively movable to transfer the point of operation of the operating means around the shoe, feeding mechanism acting automatically on the shoe, mechanism acting automatically to 45 correct the relative position of the jack and operating means to present the shoe properly to the operating means as the point of operation is transferred around the shoe, and supplemental feeding mechanism for imparting relative feeding movements to the jack and operating means, substantially as described.

13. An automatic shoe machine, having, in combination, means for operating on a 55 shoe, feeding mechanism acting directly on the shoe, a shoe supporting jack movable to transfer the point of operation of the operating means around the shoe, mechanism acting automatically to correct the relative 60 position of the jack and operating means to present the shoe properly to the operating means, and supplemental feeding mechanism for imparting feeding movements to the jack corresponding to the feeding movements 65 imparting to the shoe by the feeding

devices engaging therewith, substantially as described.

14. An automatic shoe machine, having, in combination, means for operating on a shoe, feeding mechanism acting directly on the shoe, a shoe supporting jack movable to transfer the point of operation of the operating means around the shoe, mechanism acting automatically to correct the relative position of the jack and operating means to present the shoe properly to the operating means, supplemental feeding mechanism for imparting feeding movements to the jack, and mechanism acting to automatically vary the feeding movements of the supplemental feeding mechanism in accordance with the variations in the movements imparted to the shoe by the devices engaging therewith caused by the relative corrective movements of the jack and operating means, substantially as described.

15. An automatic shoe machine, having, in combination, means for operating on a shoe, a support for said operating means and a shoe supporting jack relatively movable to transfer the point of operation of said means around the shoe, mechanism acting automatically to relatively tip the support and jack as the point of operation is transferred around the shoe, feeding mechanism acting directly on the shoe, supplemental feeding mechanism for imparting relative feeding movements to the jack and operating means, and mechanism acting automatically to vary the feeding movements of the supplemental mechanism in accordance with the relative tipping movements of the jack and operating means, substantially as described.

16. An automatic shoe machine, having, in combination, means for operating on a shoe, a support for said means, a shoe supporting jack movable to transfer the point of operation around the shoe, mechanism acting automatically to impart longitudinal tipping movements to the support for the operating means, feeding mechanism acting directly upon the shoe, supplemental feeding mechanism for imparting feeding movements to the jack, and mechanism acting automatically to vary the feeding movements imparted to the jack in accordance with the longitudinal tipping of the support for the operating means, substantially as described.

17. An automatic shoe machine, having, in combination, means for operating on a shoe, a shoe supporting jack movable to transfer the point of operation around the shoe, feeding mechanism acting directly on the shoe, mechanism acting automatically to swing the jack to correct the relative position of the jack and operating means, supplemental feeding mechanism for imparting feeding movements to the jack, and mechanism for varying the feeding movements of

- the supplemental feeding mechanism in accordance with the swinging movements imparted to the jack, substantially as described.
18. An automatic shoe machine, having, in combination, means for operating on a shoe, a shoe supporting jack movable to transfer the point of operation around the shoe, mechanism acting automatically to swing the jack to correct the relative position of the jack and operating means, a plate connected to move with the jack, and a feeding gripper acting to intermittently engage the plate and impart feeding movements to the jack, substantially as described.
19. An automatic shoe machine, having, in combination, means for operating on a shoe, a shoe supporting jack movable to transfer the point of operation around the shoe, a plate connected to move with the jack, and a feeding gripper acting to intermittently engage the plate and impart feeding movements to the jack, substantially as described.
20. An automatic shoe machine, having, in combination, means for operating on a shoe, a shoe supporting jack movable to transfer the point of operation around the shoe, mechanism acting automatically to swing the jack to correct the relative position of the jack and operating means, a plate connected to move with the jack, and a feeding gripper acting to intermittently engage the plate and impart feeding movements to the jack, substantially as described.
21. An automatic shoe machine, having, in combination, means for operating on a shoe, a shoe supporting jack movable to transfer the point of operation around the shoe, a plate connected to move with the jack and having the general outline of a shoe sole carried by the jack, and a feeding gripper acting to intermittently grip the plate and impart feeding movements thereto, substantially as described.
22. An automatic shoe machine, having, in combination, means for operating on a shoe and a shoe supporting jack relatively movable to transfer the point of operation of said means around the shoe, mechanism acting intermittently to correct the relative position of the operating means and shoe as the point of operation of the operating means is transferred around the shoe, and means for controlling the intervals between successive operations of the correcting mechanism and for timing the operation of the correcting mechanism with relation to the operation of the means for operating on the shoe, substantially as described.
23. An automatic shoe machine, having, in combination, means for operating on a shoe, a jack, mechanism for intermittently correcting the relative position of the operating means and jack, controlling mechanism for determining the intervals at which the correcting mechanism is thrown into operation and for timing the operation of the correcting mechanism with relation to the operation of the means for operating on the shoe, substantially as described.
24. An automatic shoe machine, having, in combination, means for operating on a shoe and a shoe supporting jack relatively movable to transfer the point of operation of said means around the shoe, mechanism for correcting the relative position of the operating means and jack, a controller provided with a series of trips acting successively as the point of operation is transferred around the shoe to render the correcting mechanism operable, and means for timing the operation of the correcting mechanism with relation to the operation of the means for operating on the shoe, substantially as described.
25. An automatic shoe machine, having, in combination, means for operating on a shoe, a jack, mechanism for intermittently correcting the relative position of the operating means and jack, controlling mechanism connected with the jack for determining the intervals at which the correcting mechanism may be thrown into operation, and means for timing the operation of the correcting mechanism with relation to the operation of the means for operating on the shoe, substantially as described.
26. An automatic shoe machine, having, in combination, means for operating on a shoe, a jack, mechanism for intermittently correcting the relative position of the operating means and jack, a controller provided with a series of trips acting successively as the point of operation of the operating means is transferred around the shoe to render the correcting mechanism operable, and means for timing the operation of the correcting mechanism with relation to the operation of the means for operating on the shoe, substantially as described.
27. An automatic shoe machine, having, in combination, means for operating on a shoe, a shoe supporting jack movable to transfer the point of operation around the shoe, mechanism for intermittently correcting the relative position of the operating means and jack, a controller connected to move in unison with the jack and provided with a series of trips acting successively as the point of operation of the operating means is transferred around the shoe to render the correcting mechanism operable, and means for timing the operation of the correcting mechanism with relation to the operation of the means for operating on the shoe, substantially as described.
28. An automatic shoe machine, having, in combination, means for operating on a shoe, a shoe supporting jack relatively movable to transfer the point of operation of the

- operating means around the shoe, intermittently acting feeding mechanism, mechanism for correcting the relative position of the operating means and jack, controlling mechanism for determining the intervals at which the correcting mechanism may be thrown into operation during the travel of the point of operation of the operating means around the shoe, and mechanism acting between successive feeding movements to time the operation of the correcting mechanism, substantially as described. 29. An automatic shoe machine, having in combination, means for operating on a shoe, a jack, mechanism for correcting the relative position of the operating means and jack, mechanism acting at regular periods in the operation of the operating means for throwing the correcting mechanism into operation, and devices operated at varying intervals for controlling the action of said latter mechanism, substantially as described. 30. An automatic shoe machine, having, in combination, means for operating on a shoe, a jack, mechanism for correcting the relative position of the operating means and jack, mechanism acting at regular periods in the operation of the operating means for throwing the correcting mechanism into operation, and devices for rendering said latter mechanism ineffective operated at varying intervals to render said correcting mechanism effective, substantially as described. 31. An automatic shoe machine, having, in combination, means for operating on a shoe, a jack relatively movable to transfer the point of operation of the operating means around the shoe, mechanism for correcting the relative position of the operating means and jack, mechanism acting at regular periods in the operation of the operating means for throwing the correcting mechanism into operation, and devices for render-
- ing said latter mechanism ineffective operated at predetermined intervals during the transfer of the point of operation of the operating means around the shoe to render said correcting mechanism effective, substantially as described. 32. An automatic shoe machine, having, in combination, means for operating on a shoe, a shoe supporting jack movable to transfer the point of operation around the shoe, a plate connected to move with the jack, and means acting on the plate to intermittently feed the jack and cause it to swing about the point of operation, substantially as described. 33. An automatic shoe machine, having, in combination, means for operating on a shoe, a shoe supporting jack longitudinally movable and rotatable to transfer the point of operation of the operating means around the shoe, a plate connected with the jack, and means engaging the plate to intermittently feed the jack and to constrain it to swing about the point of operation of the operating means, substantially as described. 34. An automatic shoe machine, having, in combination, means for operating on a shoe, a shoe supporting jack longitudinally movable and rotatable to transfer the point of operation of the operating means around the shoe, mechanism acting automatically as the point of operation is transferred around the shoe to impart turning movements to the jack, and devices other than the operating means and turning mechanism to determine the point about which the jack swings, substantially as described. In testimony whereof I affix my signature, in presence of two witnesses.
